John Scoville
Letter's Patent.

The Schedule is referred to in this Letter Patent and making part of the same containing a description in the words of the said John Scoville himself of his churning machine.

The Body of the Churn is to be round like a common churn, in the inside to give motion to the cream or milk, so to be two dashers in the form of a reel which are to turn round on a spindle passing through the centre of the churn from top to bottom. The large dasher is to be fixed with four slats from the ends of the arms at top and bottom and are to stand perpendicular in range with the slats of the churn, and are to pass (when turned round) near the inside of the slats of the churn. The small dasher is made like the other only smaller so as to turn round with in the large one. This small dasher is fixed to the spindle upon which are fixed two trundle heads above the body of the Churn. The upper trundle head is fastened to the spindle. The lower trundle head is fixed to a Box made over the said spindle and extends down and connects with the arms or top plate of the large dasher. These two trundle heads are put in motion by turning a crank on the shaft or spindle of which is a cog wheel which at top and bottom intersects said trundle heads the topmost of which being connected with the spindle to which is connected the small dasher. That dasher is turned one way and the lower trundle head ^{being} connected with the said Box and that Box with the upper end or arms of the large dasher. That dasher is turned an opposite way, so that the Box, when in motion turns different ways by which means the cream or milk is immediately changed into Butter. The upper trundle head is so fixed that it can easily be taken off from the cog wheel, so that the small dasher is immediately stopped, and the large dasher may go round and rolled. The Butter ready to be taken out of the churn. On the outside of the churn two posts may be fixed, through one of which the spindle may pass to which the crank is fixed, and across the tops of these posts a slot must go into which the top of said perpendicular spindle is to be fixed. This machine may be set in motion by hand by water or by a machine going by weight.
